SUSPENDER ADJUSTING DEVICE

John M. Clark, Detroit, Mich., assignor to Universal Button Fastening & Button Company, Detroit, Mich., a corporation of Michigan

Application January 17, 1933, Serial No. 652,170

4 Claims. (Cl. 24—73)

This invention relates to suspender adjusting devices, and among other objects aims to provide a compact and inexpensive device for securing a suspender strap.

5 The nature of the invention may be readily understood by reference to one illustrative construction embodying the invention and shown in the accompanying drawing.

In said drawing:

10 Fig. 1 is an elevation of the device;

Fig. 2 is a vertical section of the device taken approximately on the plane 2—2 of Fig. 1 illustrating the bars drawn together to grip a suspender strap when tension is applied thereto;

15 Fig. 3 is a view illustrating how the slide portion of the device may flex or hinge relative to the button loop so as not to transmit any detaching force thereto; and

20 Fig. 4 is a transverse section of the device taken approximately on the plane 4—4 of Fig. 1.

The illustrative device combines in one unit 10 the functions of a so-called suspender slide and a suspender loop by which the suspender may be releasably secured or connected to the 25 garment, as for example, the bib 11 of a pair of overalls. The slide element permits adjustment of the length of the suspender strap. The combined slide and loop is advantageously made of wire which in the present instance is about .080 30 to .085 inch in diameter. The wire is preferably brass plated or otherwise coated to provide an attractive as well as a protective finish.

The combined unit is here shown as comprising 35 a frame 12 made of wire bent into a generally rectangular shape and having its extremities terminating at the lower side of the loop in spaced eyes 13 formed to provide transversely elongated eye openings 14 whose lower sides 15 incline or diverge downwardly. Connected with 40 the sides 16 of the slide frame, in this instance by eyes 17 and 18 which embrace the sides of the slide frame, is a pair of parallel bars 19 and 20 around which the suspender strap 21 is adapted to be threaded for purposes of adjustment and attachment to the device. As here shown, the lower bar 20 is freely movable up and down the sides of the slide frame and is capable of a slight axial rotation relative to such frame by reason of the fact that the eyes 18 are somewhat larger than the diameter of the sides of the frame. Teeth 22 may advantageously be formed in bar 20 in such position as to engage the suspender strap and to cooperate in preventing slippage. In the present instance the gripping teeth are rounded and formed by pinching

out integral portions of the metal of the bar. The upper bar 19 is here shown held against displacement in the frame of the slide by having its eyes embrace inwardly offset portions 23 of the sides of the frame which serve to prevent movement of the eyes along the frame sides.

5 As illustrated in Fig. 2, the suspender strap is threaded between the top 24 of the slide frame and the bar 19, thence around the lower bar 20 and over the upper bar 19 in direct engagement with the latter and underneath the other strand of the suspender strap. Tension applied to the strap causes the lower bar 20 to rise, thereby gripping the suspender strap tightly between the bars. Where teeth are employed on the lower bar the latter also cooperate to prevent slippage, although without them the suspender strap is undoubtedly gripped so tightly between the bars as to preclude any slippage or alteration of adjustment in the suspender strap length. Adjustment of the strap may be easily made by relaxing tension thereon and by permitting the bars to separate sufficiently to allow the suspender strap to be shifted relative thereto. The capacity of the bars to separate also facilitates the initial 15 assembly of the suspender strap and adjusting device at the factory.

20 Hinged to the lower portion of the slide, in this case to the eyes 13, is a button engaging loop 25 provided with eyes 26 which loosely embrace the lower sides 15 of the eyes. The upper or slide portion of the device is therefore free to flex relative to the button engaging loop 25 and therefore does not tend to pry the latter from the button or transmit a downward detaching 25 force thereto when the suspender strap becomes slack. Instead when the suspender strap becomes slack, the loop 25 is allowed to remain in its normal position and the slide may flex forwardly relative thereto.

30 The loop is applied to a button by passing the button head (see Fig. 2) through the space 27 between the loop and the lower bar; the latter in this case may be raised if necessary to allow greater freedom for insertion of the button head. 35 The shank of the button is then caused to pass through the restricted space 28 between the eyes 13 into loop 25 which is substantially smaller than the button head to prevent the button head from escaping. In normal or unstrained condition the restricted space 28 between the eyes 13 is substantially narrower than the diameter of the button shank to prevent accidental passage of the button from the button loop into the space 40 50 55 27 (in the event of slackening of the suspender

strap, as when the wearer bends over) where the loop may become detached from the button. The portions of the wire immediately above and below the restricted space 28 are preferably curved as at 5 29 and 30 to provide cam surfaces to be engaged by the button shank to force the eyes 13 sufficiently apart to allow the button shank to pass. The natural stiffness of the wire is however sufficient to prevent such separation of the eyes accidentally. The application of manual force is 10 necessary to cause the button shank to pass either into or out of the loop. The sides 16 of the frame not being rigidly held by the bar 20 are free to flex upon separation of the eyes 13 as 15 the button shank passes between them. It will be noted that the eyes 26 of the button loop are separated sufficiently not to interfere with the yielding movements of the eyes 13 as the shank of the button passes between them.

20 When tension is placed upon the button and the button loop 25, the eyes 26 tend to slide down the inclined or diverging portions 15 of the eyes 13, thus setting up a positive component of force which tends to press the eyes 13 together and 25 to maintain the space 28 in restricted condition. Release of such tension of course leaves the eyes free to flex as aforesaid.

Slacking of the tension in the suspender strap (as when the wearer bends over) leaves the lower 30 bar free to descend somewhat to a position underneath the edge of the button head and to cooperate to prevent accidental detachment of the button from the loop.

Cost of manufacture is substantially lessened 35 by eliminating the necessity of making a closed frame for the slide wherein the ends of the wire would have to be welded or otherwise fastened together. Such weld usually occurs in the top bar, making it desirable to conceal the latter. 40 In the present instance these ends are bent to form the elongated eyes 13, and the top portion of the slide frame containing no joint, need not be concealed.

Obviously the invention is not limited to the 45 details of the illustrative construction since these may be variously modified. Moreover it is not indispensable that all features of the invention be used conjointly since various features may be used to advantage in different combinations 50 and sub-combinations.

Having described my invention, I claim:

1. An article of the character described comprising a rectangular wire frame having sides and ends, the ends of the wire terminating at 55 one end of said frame and being respectively formed into spaced eyes, a button loop hinged to said eyes, and a pair of parallel bars connected to the sides of said frame and extending trans-

versely across said frame, the lower one of said bars being loosely connected to the sides of the frame to leave the latter free to flex as a button passes between said eyes.

2. An article of manufacture comprising a generally rectangular wire frame having sides and ends, the ends of the wire forming the frame terminating at one end of the frame in spaced eyes, a pair of upper and lower spaced parallel bars connected to the sides of the frame and extending transversely across the frame, the lower sides of said eyes diverging downwardly, and a button loop hinged to the lower sides of said eyes whereby tension applied to said loop tends to draw said eyes together, the said lower bar loosely embracing the sides of said frame to allow the same to yield freely upon movement of said eyes.

3. An article of manufacture comprising a rectangular frame having sides and ends and formed from relatively stiff but resilient wire whose ends terminate at one end of the frame in spaced relationship, a pair of parallel bars extending transversely across the frame and having eyes embracing the sides of the frame, the lower portion of said frame being provided with a button supporting loop, terminal portions of said wire frame adjacent the loop being spaced apart a distance less than the diameter of the button shank and requiring separation to permit the passage of the button shank from engagement with the loop, thereby resisting accidental detachment of the button from the loop, said wire frame providing elongated free resilient side and terminal portions extending from the bars to the spaced portions to compensate for the stiffness of the wire and allow resilient separation of said spaced portions upon passage of a button shank.

4. A suspender adjusting device comprising a generally rectangular frame having sides and ends, the lower end of said frame having spaced terminals, a pair of parallel bars extending transversely thereof, the upper one of said bars being fastened to the sides of said frame so as not to move vertically therein, the lower one of said bars loosely engaging the sides of said frame and being movable vertically therein to cooperate with the other bar in gripping a suspender strap, the sides of said frame below the upper bar providing elongated yielding means to allow said terminals to be separated, and a button loop hinged to the terminals at the lower side of the said frame, said movable lower bar being adapted to drop when the suspender strap is slackened into proximity with the button loop.

JOHN M. CLARK.
